UNITED STATES PATENT OFFICE.

EDWIN O. READ, OF NEW YORK, N. Y.

SASH-FASTENER.

SPECIFICATION forming part of Letters Patent No. 531,646, dated January 1, 1895.

Application filed December 7, 1893. Serial No. 492,983. (No model.)

To all whom it may concern:

Be it known that I, EDWIN O. READ, a citizen of the United States, and a resident of New York, in the county of New York, State 5 of New York, have invented a certain new and useful Improvement in Sash-Fasteners, of which the following is a specification.

My invention relates to improvements in window catches, and it is the purpose of the 10 improvement to provide a simple, cheap, and efficient catch, which shall be difficult of reach to a person attempting to open a window surreptitiously from the outside, and yet shall be easily operated by persons in the house, 15 and shall not mar the window casing or frame.

Referring to the drawings which accompany the specification to aid the description, Figure 1 is a perspective view of the catch in the locked position, omitting the socket 20 or thimble which is engaged by the head of the catch. Fig. 2 is a sectional elevation, as on the line $x x$ of Fig. 1, but also showing the upper and lower sashes in broken view and the socket for the head of the catch. Fig. 3 25 shows the same parts as Fig. 2, but the catch is represented in the open position.

The catch is applicable to those windows of which both sashes are movable, and to those of which only the lower sash is movable. The 30 drawings show it applied to windows of the former kind.

The catch proper A, of any suitable material, as brass, and shaped as shown in the figures, is provided with a head a , which is 35 adapted to enter a socket or thimble B secured in the present case to the side of the frame W of the upper sash. When only the lower sash is movable the socket B may be secured to the bead which separates the two 40 sashes, or to the upper sash. Said catch A has a thumb piece c , and is pivoted at its lower end in ears $d d$ on a plate D, which is screwed to the top of the lower sash behind the stile W of the upper sash, so as to be out of reach 45 of any tool that may be worked up the joint j between the two sashes. The lower end of the catch A is provided with angled cam-surfaces, $e f$, as shown, one of which bears on the spring G when the catch is engaged into 50 its socket B and the other bears on said spring G when the catch is turned back, (Figs. 2 and 3.) Said cam-surface e is formed, as shown on the drawings, at an angle upwardly and

outwardly with the standard or upright part, a^2 , of the catch A, so that the effect of the 55 pressure of the spring G on said cam surface e is to continually force the standard off center outwardly and press the head a into the socket B. This shape of said cam-surface e effectually resists any attempt to dislodge 60 the head a from the socket B by jarring the sash. The plate D is beveled at d' as shown, to afford play to the spring G. It will be manifest that the effect of said spring G is to hold the catch firmly in the locked position, and to prevent forcing it out of the 65 socket B by shaking the sash W or W'.

As hereinbefore stated the catch A may be employed in the case of windows whereof only the lower sash moves. The socket B 70 will then be set on the bead B' which holds the lower sash in position.

When used with windows whereof both the upper and lower sashes move it will be apparent that the catch acts at the same time 75 to lock both sashes. If desired, in all cases there may be additional thimbles at various heights to retain the lower sash in any raised position.

Now, having described my improvement, I 80 claim as my invention—

In a window fastener, the combination of a socket, an arm provided with a head that is adapted to enter said socket—and said arm being pivoted at its lower end to a base plate, 85 cam surfaces $e f$ on the lower end of said arm arranged at an angle to each other, and said cam surface e also arranged at an angle upwardly and outwardly with said arm, a flat spring fastened on said base plate and having 90 an end adapted to be engaged by said cam surfaces $e f$ according as the catch is in the vertical or the horizontal position respectively, and said spring being also adapted to force said arm outward from the perpendicular and press said head into said socket, 95 substantially as described.

In testimony that I claim the foregoing as my invention I have signed my name, in presence of two witnesses, this 21st day of November, 1893.

EDWIN O. READ.
